(57) **CLAIM**

The ornamental design for a razor tray, as shown and described.

DESCRIPTION

FIG. 1 is a front perspective view of the razor tray, showing the new design;

FIG. 2 is a front view of the razor tray;

FIG. 3 is a rear view of the razor tray;

FIG. 4 is a side view of the razor tray;

FIG. 5 is another side view of the razor tray;

FIG. 6 is a top view of the razor tray;

FIG. 7 is a bottom view of the razor tray;

FIG. 8 is a front perspective view of the razor tray with a razor in it;

FIG. 9 is a front view of the razor tray with a razor in it;

FIG. 10 is a rear view of the razor tray with a razor in it;

FIG. 11 is a side view of the razor tray with a razor in it;

FIG. 12 is another side view of the razor tray with a razor in it;

FIG. 13 is a top view of the razor tray with a razor in it; and,

FIG. 14 is a bottom view of the razor tray with a razor in it.

The broken lines showing various elements of the razor in the razor tray are included for the purpose of illustrating non-claimed subject matter and forms no part of the claimed design.
